ATTORNEY

UNITED STATES PATENT OFFICE.

CHARLES E. AVERY, OF EAST ORANGE, NEW JERSEY, ASSIGNOR TO MANHATTAN ELECTRICAL SUPPLY COMPANY, INCORPORATED, OF JERSEY CITY, NEW JERSEY, A CORPORATION OF MASSACHUSETTS.

TOGGLE SWITCH.

Application filed November 20, 1922. Serial No. 602,083.

To all whom it may concern:

Be it known that I, CHARLES E. AVERY, a citizen of the United States of America, and residing at East Orange, in the county of Essex and State of New Jersey, have invented new and useful Improvements in Toggle Switches, of which the following is a specification.

My invention relates particularly to what are sometimes called toggle or tumbler switches, and particularly to the actuating mechanism.

The main object is to provide a simple but reliable mechanism which can be readily made and easily operated and which is small and compact.

Another object is to provide a construction which can be assembled without the use of rivets.

Another object is to provide a construction, many of the parts of which can be interchangeably used for either a toggle switch or a push button switch.

In its preferred form the invention contemplates the use of a pivoted contact carrier to which is loosely hinged a throwing link. The actuator is hinged to the bridge or cross bar and serves to hold the other parts in place in the receptacle. This actuator is of such a nature that it can be readily attached to the bridge, which is also adapted to be used in a push button switch, together with the other parts of the structure.

Fig. 1 is a front view of a switch embodying the improvements of my invention,

Fig. 2 is a longitudinal sectional view and side elevation of the same,

Fig. 3 is a transverse sectional view of the same,

Fig. 4 is an enlarged side view showing the contact carrier and the supporting frame,

Fig. 5 is a perspective view of the bridge and actuator,

Fig. 6 is a side view of the same,

Fig. 7 is a bottom view of the same,

Fig. 8 is a plan view of the blank from which the bridge is formed,

Fig. 9 is a detailed view of the escutcheon plate,

Fig. 10 is a side view of a modified form of actuator,

Fig. 11 is an edge view of the same, show-

ing a section of the supporting bridge and escutcheon plate.

The body or receptacle 12 may be formed of insulating material, such as porcelain or molded composition and contains the necessary stationary contact or contacts of suitable form suitably secured in place.

The movable or swinging switch member 13 is suitably secured to a carrier 14, which has projecting bearings 15 hung in the side standards 16, which project from one end of the frame 17. This carrier is of U-shape and its bottom bar 18 swings between the standards 16 and the shoulders 19, which serve as stops to limit the throw of the carrier and movable switch member.

The frame 17 may be conveniently positioned within the receptacle, for instance, by means of the lugs such as 20 and 21 properly located with respect to the projections and recesses within the receptacle. The construction is such, however, that as will be hereinafter understood, no attaching screws are required for holding the frame in place.

Hinged loosely to the cross bar 18 is a link 22, which carries the spring 23. This spring is held in place on the link by a washer 24, and the link is provided with lugs 25, which serve as stops for the washer 24. This washer 24 may also have one or more side flanges 26 adapted to engage the edges of the cross bar 18, when the spring is fully compressed.

The actuating device consists of a lever or handle 27, and a rocker 28 suitably secured together as, for instance, by the rivet heads 29. The rocker is provided with outwardly projecting pivot pins 30 supported in lugs 31 at the sides of the bridge 32. The bridge is slotted centrally at 33 and provided with openings 33' at the ends thereof, which are adapted to accommodate push buttons when the bridge is used in a push button switch. The lever 27 extends through the slot 33 and the shoulders 34 on the rocker serve as stops which engage the lower face of the bridge as the actuator is swung from side to side. The tip 35 of the actuating rocker is preferably rather sharp and adapted to engage the washer 24 between the arms of the link 22, as shown in Fig. 2. This rocker is also provided with a slot 36 to allow for

the movement of the arms of the link, as the actuator is swinging back and forth.

The bridge 32 is adapted to be suitably secured to the top of the receptacle 12 in any suitable manner, as, for instance, by means of the usual screws 37. A face plate, such as 38 is adapted to be secured in the usual manner to the bridge, for instance, by means of one or more screws 39. In order to fill the central opening in the face plate and provide a finish for the interior parts at the junction of the operating lever 27 and the bridge 32, I provide an escutcheon plate 40 through which the lever projects and which fits within the central opening of the face plate. This escutcheon is conveniently secured to the bridge 32, for instance, by means of fingers 41, adapted to be bent around the edges of the bridge, as shown, for instance, in Figs. 6 and 7.

It will be noted that when the parts are assembled, as shown in Figs. 2 and 3, the rocker 28 holds the spring 23 under compression and thus holds the carrier 14 in place in the frame 17 and the frame in place in the receptacle 12, without the need of any attaching screws, thus doing away with the necessity of screws ordinarily employed for such purpose. The carrier and frame are so constructed that they can be readily assembled without the use of tools. Since no rivets or pins are required, when the actuating lever 27 is tilted, the rocker, of course, moves with it and compresses the spring until the line of centers is passed, whereupon the spring snaps the switch contact member to the opposite position, making or breaking the circuit as the case may be. In case the switch contacts should stick, however, the flange 26 of the washer 24 will be forced against the opposite edge of the carrier bar 18, after the lug passes beyond the center line and thus power will be directly applied from the hand through the rocker to start the movement of the carrier, which once started will be completed by the kick of the spring.

The rocker may be formed and connected to the bridge by bending over the ears or lugs 31, or the bridge ears may be bent over and the rocker pins inserted by springing the sides of the bridge apart. Similarly the rocker may be detached from the bridge and another bridge and push button substituted, if desired.

Other forms of actuating levers and rockers may be employed, as indicated, for instance, in Figs. 10 and 11, where I have shown the rocker having side plates 43 connected by the tip 44. In this case the side plates have outwardly extending pivot pins 45 adapted to be supported in the bridge. The lever 36 may be suitably secured to the rocker, for instance, by rivets 47 and 48. Other changes may be made in the details

of construction within the scope of my invention.

I claim:

1. A switch receptacle, a frame mounted therein, a carrier detachably hinged to said frame, a link hinged at one end to said carrier and having its opposite end slotted, a spring and slotted washer on the slotted end of said link, a bridge, a lever and rocker hinged thereto and having a slotted arm engaging said washer and in the slot of said link. 75

2. A switch construction comprising a receptacle open at the front, a frame and contact carrier removably mounted therein, a bridge detachably secured to the front of said receptacle independently of said frame and carrier, and an actuating lever and rocker carried by said bridge and holding said carrier in place in said frame. 80 85

3. An electric switch construction comprising a receptacle, a frame positioned therein, a swinging carrier mounted in said frame, a spring link secured to said carrier, a bridge detachably secured to said receptacle and an actuating lever and rocker hinged to said bridge and having an arm engaging said spring link to operate the same and to hold said carrier and frame in said receptacle. 90 95

4. An electric switch comprising a receptacle, a frame and swinging carrier mounted therein, a link hinged to said carrier, a washer and spring secured on said link, a detachable bridge and a lever and rocker hinged to said bridge having an arm engaging said link and washer for operating the same and holding said carrier and frame in position in said receptacle. 100 105

5. An electric switch comprising a receptacle, a frame removably mounted therein, a carrier detachably hinged to said frame, a spring link connected to said carrier and removable therewith, a bridge detachably secured to said receptacle, a lever and rocker hinged to said bridge and removable therewith, said rocker having an arm engaging said link to operate the same and serving to hold said carrier in said frame and said frame in said receptacle. 110 115

6. An electric switch comprising a receptacle, a frame mounted therein, a carrier detachably hinged to said frame, a spring link hinged to said carrier, a bridge detachably secured to said receptacle, a lever and rocker hinged to said bridge and detachable therewith, said rocker having an arm engaging said link to operate the same and serving through said spring link to hold said carrier in said frame. 120 125

7. In a switch a receptacle open at the front, a frame removably mounted therein, a switch carrier, removably and pivotally mounted in said frame, a combined throwing spring and link hingedly carried by said 130

- carrier, a bridge detachably secured to the front of said receptacle, and a rocker and operating lever carried by said bridge, said rocker operatively engaging said link and holding said link and said carrier in place, said bridge and rocker being removable independently of said carrier. 45
8. A U-shaped carrier, a link hinged to the cross bar thereof, a spring on said link, a washer on said link having a flange adapted to engage said cross bar to start the movement thereof, a hinged operating lever, and a rocker secured thereto and engaging said link and said washer to operate the carrier. 50
- 10 9. In a switch a receptacle open at the front, a cross bar anchorage member detachably secured to the front face of said receptacle and having a central longitudinal slot and lugs depending from the edges of said anchorage member adjacent said slot, an operating member pivoted in said lugs and having a handle extending through said slot and a switch member held in place by said operating member and removable only when said anchorage member is removed. 55
- 15 10. A bridge for snap switches comprising a strip of sheet metal having apertures at its opposite ends adapted to receive means for securing the bridge to a wall box, said strip having a pair of screw threaded openings near each end to receive face plate and receptacle screws respectively, and the center of said strip comprising opposed arcuate portions having apertures adapted to receive push buttons and said arcuate portions being connected by two central portions separated from one another to form an operating lever-receiving-slot, said central portions having laterally extending ears forming bearings for said operating lever. 60
- 20 11. An interchangeable bridge piece for snap switches comprising a strip of metal having screw seats for attachment to a receptacle, openings for push buttons, a central lever-slot connecting said openings, and bearing ears on opposite sides of said slot. 65
- 25 12. A bridge having a slot and bearing members at the sides thereof, a handle hinged to said bearing members and extending through said slot and an escutcheon plate having lugs secured to said bridge at the edges thereof adjacent said handle. 70
- 30 13. In an electric switch, a bridge member having a slot and depending lugs adjacent thereto, a rocker having pins pivotally supported in said lugs and having arms adapted to abut against the rear face of said bridge member, a handle extending through said slot and securely attached to said rocker 75
- 35 14. An escutcheon plate for switches comprising a dome shaped plate having a diametric slot receptive of an operating lever, said plate having two curved opposed extensions each of which terminates in concentric ears adapted to secure the plate to a bridge piece. 80
- 40 15. An escutcheon plate for switches comprising a dome shaped plate having a diametric slot receptive of an operating lever, and having two extensions terminating in ears adapted to secure the plate to a bridge piece. 85
- 45 16. An escutcheon plate for a snap switch having a raised central portion with a lever receiving slot and a base flange terminating in two oppositely directed bendable ears on each side of said slot. 90
- 50 17. An interchangeable bridge piece for an electric snap switch comprising a strip of metal having means for attachment to a receptacle and having a central lever receiving slot and openings for push buttons at the opposite ends thereof and bearing lugs at opposite sides of the central slot adapted to support a rocker member. 95

CHARLES E. AVERY.
